[57] CLAIM

The ornamental design for a chair, substantially as shown and described.

DESCRIPTION

FIG. 1 is a perspective view of a chair illustrating my new design;

FIG. 2 is a top plan view thereof;

FIG. 3 is a front elevational view thereof;

FIG. 4 is a side elevational view thereof; and

FIG. 5 is a rear elevational view thereof.

The design is characterized, as best illustrated in FIG. 4, by trapezoidal side supports each including a base member, front and rear inwardly and upwardly directed side members and a top member parallel with and shorter than the base member. The front and rear side members are interconnected by sloped cross bars which slope slightly downwardly from front to rear. The seat member is mounted to and supported by the sloped cross bars and extends substantially beyond the front side members while the back rest is mounted to the rearward side members at an angle so that it lies in a plane which intersects with the rear portion of the seat member.
